AUTOMATIC TRAIN SIGNAL FOR LEVEL CROSSINGS

Aristide Riccardi, Rome, Italy

Application August 20, 1931, Serial No. 558,218
In Italy August 23, 1930

4 Claims. (CL 246—126)

Various systems of train signals especially adapted to be used at level crossings, in which the motive power is furnished by the passage of the train over the track section comprising the signal's mechanism, have been proposed and adopted. Some of these arrangements include the provision of automatic visual or optical signals actuated by the flanges of the car wheel passing over a pedal provided on the rail, and 5 detent devices operated by an electromagnet for permitting the operation of the signal at the required time, as well as magneto-electric generators arranged to be operated by the passing trains to produce a current for the purpose of releasing the above mentioned detent.

It has also been proposed to utilize the flexion of the rail produced by the passage of the successive car wheels over it, for transmitting the said movement, by means of pedals or levers, 20 directly to magneto-electric generators, the current thus produced being employed for actuating the signals.

All these systems, and especially the one last mentioned have not proved to be efficient both for the reason that full advantage has not been taken of the rail's flexion produced by the train wheels for the double conversion of power, viz., 25 into electric power and back to mechanical power, and also by the fact that the said proposed arrangements are not fully automatic, requiring the use of outside sources of power and also requiring to be adjusted as to the length of time in which it is desired to maintain the signal effective.

35 By the present invention, the said drawbacks are eliminated as it comprises a completely self contained signalling device, which, after having signalled the passage of a train near a level crossing, or other particular portion of the railway track, is returned by the same train the passage of which it has signalled, back to normal working trim for signalling the passage of another train over the same track section.

The present invention relates to a system of 45 automatic signalling especially adapted for the above said purposes comprising two track sections placed at a convenient distance from each other, the first of which comprises an electromagnet inserted in an electric circuit which is acted upon by the first wheel of the train passing over a control mechanism placed over the said rail section, thus producing the release of a weight held normally in a lifted position by the armature of the said electromagnet, causing the fall of the said weight which actuates the signal.

while the other track section over which the train passes subsequently is provided with a lever or pedal, placed under one of the rails of the said section, about midway between two consecutive sleepers, which lever or pedal receives and transmits the alternate movements of flexion of the rail caused by the successive passage of the cars over it, to a device suitable for transmitting the said alternate movements and for storing the energy produced thereby by raising the aforesaid 10 weight.

The autonomy of the apparatus, as regards the power required, is by no means impaired by use of supplementary voltaic cells or accumulators, as these sources of electric current, when properly attended to, constitute an absolutely safe and autonomous source of energy.

In order that the invention may be better understood, a signalling apparatus constructed and operated according to the principle of the invention will, by way of illustration, now be described with reference to the annexed drawings, 20 in which:

Fig. 1 shows schematically the general arrangement of the various parts included in the signal apparatus installed in a portion of a double track road.

Fig. 2 shows the starting apparatus which utilizes the flexion of the rail, for actuating the signalling device as the train passes over it.

Fig. 3 shows a form of embodiment of the electric contact device.

Fig. 4 is a section taken through the base of the signal column.

Fig. 5 is a section taken through the same base 35 of the column in a plane orthogonal to the plane of Fig. 4.

Fig. 6 is a longitudinal section taken through the top of the column, a portion thereof being broken away.

Fig. 7 shows in elevation, in a plane orthogonal to the plane of Fig. 6, the upper part of the signal's column, portions being broken away.

Fig. 8 shows the detail of the re-charging device in vertical section taken through a plane 45 normal to the track.

Fig. 9 shows a sectional plan taken through the weight of the recharging apparatus.

Fig. 10 shows the detail of the stop device for the weight of the recharging apparatus.

Fig. 11 shows schematically the arrangement of the apparatus used in the case of a single track, in order to prevent the train, after having passed in front of the level crossing, from restart-

ing the signalling apparatus when passing over the second contact apparatus.

The apparatus as exemplified by the embodiment of the invention illustrated in the drawings comprises substantially, as shown in Fig. 1, a controlling mechanism, or contact device A placed at a certain distance from the level crossing, a signalling apparatus B placed near the level crossing, which device is actuated by means of electric current transmitted by the above said device A, and a mechanism applied to the running rail C for the supply of energy, which mechanism receives the impulses produced by the passage of the car wheels, transmitting them to a suitable device where they are transformed into energy which can be utilized.

The said mechanism applied under the rails C in correspondence to the level crossing is shown in section in Fig. 2 and is connected to the signalling apparatus B which contains all the parts required for the production of the signals. The electric circuits controlled by the contact piece A are used for starting the movement of the signalling mechanisms of the apparatus B, by means of an electromagnet 1, the winding of which is comprised in one of the said circuits, which winding actuates a small armature the movement of which produces the fall of a weight 3 rotatable together with a pivot 4 about the axis of the pivot, and connected with the signalling mechanisms.

According to a preferred form of embodiment, the excitation of electromagnet 1 is produced by connecting one pole 5 of the electromagnet to the ground T, (Figs. 1 and 2) and the other pole 6, with one terminal 7 of the rotor winding of a small magneto-electric machine through an insulated conductor 11, which may also consist of one of the rails, the other terminal 9 of the rotor winding being connected to the ground. The said magneto-electric machine forms part of the contact apparatus A. The above said rotor is mounted on a shaft 10 (Fig. 2) which carries, keyed to it, a detent bar 11 which is acted upon by a tooth 12 provided on a rod 13 which can be shifted longitudinally by means of an arm 14 of a bell-crank lever pivoted in a sleeper carrying the rail 11. The other arm 15 of the lever rests permanently, maintained by a lever 16, against the lower side of the rail's flange. When the rail 11 is flexed as a train passes over it, a pulling action is exerted upon the rod 13, which produces the partial rotation of the detent 11, and consequently also of the rotor, until the detent 11 becomes disengaged from the tooth 12 and is returned to its original position by the action of a spring applied to the shaft, which spring is not shown in the drawings. The said return movement of the detent 11 to its original position is utilized to induce in the rotor circuit of the magneto-electric machine an instantaneous current, which by exciting the electro-magnet 1, causes the latter to attract its armature thus allowing the weight 3 to drop. Tooth 12 being fitted with a spring, when returning to its original position, will re-engage the detent 11, the said operation being repeated at every successive flexion of the rail: said flexion movements cease to be effective on the signalling apparatus when the weight 3 has reached its lowermost position, the effect recommencing when it is lifted back to its normal position. The magneto-electric machine may also consist of a common spark magnet such as used on internal combustion motors.

75 The second method (Figs. 3 and 4) for excit-

ing the electromagnet 1, consists in connecting its two poles 5 and 6 (Fig. 1) with two insulated wires 19 and 17 (Fig. 3) connected with two conductor plates 7 and 9, which are normally in mutual contact and are detached at any flexing movement of the rail 11 thus breaking the circuit, through the action of the bell-crank lever 14-15 as previously described. The said circuit includes a source of electromotive force, which may be for example a cell 8", so that the armature is normally kept attracted, and only when the electromagnet becomes inoperative by the breaking of the circuit caused by the passage of a train, the armature becomes detached by its own weight thus producing the fall of the weight 3.

The signalling apparatus B (Figs. 4, 5 and 7) as previously said, contains all the signalling mechanisms and is capable of giving the following signals:

(a) An optical signal by means of an oscillating arm fitted with a disc,

(b) A luminous signal by means of a lamp which can give out continuous or intermittent light.

(c) An acoustic signal by means of bell, or the like.

(d) In case the apparatus becomes damaged, a visible indication to show that it is inoperative.

All the parts and mechanisms required to produce the above said indications are controlled by the fall of the weight 3.

The power required to carry out the said indications is as previously stated, supplied by the passage of the wheels of the cars over the point on which the mechanism A (Fig. 1) is placed, but said power is previously stored in the form of potential energy of gravity in the lifting of a heavy mass, and is afterwards utilized by the lowering of this latter through the working of the mechanisms above described.

All the parts forming the signalling apparatus B are assembled in a column 30 which carries externally the signalling parts formed by the bell 31 (Fig. 6) mounted at the top, and by the oscillating disc 32 fitted with the lamp 33 mounted near to the upper end of the column.

The bell 31, the disc 32 and the lamp 33 are arranged to start operating as shown when the first axle of the train has actuated the contact apparatus A, and from that moment until the locomotive passes over mechanism C, the bell continues to operate, which operation may consist in successive hammer blows, the disc continues to swing around its axis 34 and the lamp sends out its light, either continuous or intermittent.

The connections between the said signalling devices and the weight 3 are arranged in the following manner:

Inside the column 30 and at its base (Fig. 5) is mounted a drum 35 round which a cable 36 is wound, the cable being taken upwards along the column and being guided by two return pulleys, and its downward end, after passing over the pulleys carries at its other end a heavy mass 37 (Fig. 6).

The drum 35 is coaxial and integral with a ratchet wheel 39, (Fig. 5) on the periphery of which engage two spring pawls 40 rotatable about opposite seats provided in a supporting plate 75 (Fig. 4) and fitted with extensions 41 which rest on the periphery of a cam 42 coaxial with the wheel 39, and actuated by the rod 43 of a three

arm lever 44 (Fig. 4) and of an intermediate connecting rod 44'', by the arm 44''' integral with the pivot of rotation 4, of the weight 3, and rotatable with said weight round the axis of the pivot.

Integral with the drum 35 are a second ratchet wheel 39', which can move only in the direction of the rotation corresponding to the unwinding of cable 36 from drum 35 and a toothed wheel 45, which by means of pawls 45', 45'' carried by the wheel 45 can actuate successively, by means of the toothed wheels 46', 46'', the shaft 47 which controls the oscillations of disc 32, the shaft 48 controlling the hammer 49 of the bell 31, and the shaft 149 on which is mounted the armature of a dynamo or alternator 50, which serves to produce the electric power necessary for lighting the lamp 33.

The shaft 149 carries also keyed thereto a ratchet wheel 61 the periphery of which is engaged by the curved end of a flat spring 62, fastened at its other end (Fig. 4) to the arm 63 of a lever pivoted at 64, the other arm of which lever is connected, through a connecting rod 66, with the same arm of lever 44' which transmits the movement to the connecting rod 44'' so that when the weight 3 is lowered (Fig. 1) the spring 62 releases wheel 61.

The arrangement of spring 62 acting as a stop on the wheel 61, facilitates the starting of said wheel as well as that of the gearings connected to it, inasmuch as when it revolves round the pivot 64 to disconnect itself from wheel 61, it transmits to this latter an impulse which produces its rotation in the opposite direction to the movement which it had before it had been stopped by the spring.

The shaft 48 controls the oscillations of the bell hammer through a cam 51 keyed to it, on the periphery of which cam rests the end of a lever 52 (Fig. 4) the other arm of which lever is connected by means of a rod 64', a return lever 54 and a link 54'' with the arm 85, (Fig. 6) which carries the bell hammer 49 and has attached to it the return spring 53 (Fig. 6).

The shaft 47 (Fig. 5) controlling the oscillations of disc 32, (Fig. 6) communicates its movement through an elastic coupling 120 to a crank 55 (Fig. 4) which transmits the movement through a connecting rod 56' to a return lever 56, (Fig. 4) and a second connecting rod 56'', (Fig. 5) thereby producing an oscillating movement in the arm 57 (Fig. 7) integral with arm 57' which carries disc 32. Through the movements above described the disc 32 oscillates in a vertical plane about the axis 58 (Fig. 6) the oscillations being symmetrical with respect to a vertical line passing through said axis, said oscillations having an amplitude depending on the radius 59 of the crank which can be adjusted by a pivot 60 being suitably fixed in a groove provided on the crank 55 (Fig. 4).

In order to obviate undue efforts on the parts actuating the disc, these may be provided with suitable counterweights. The object of the elastic coupling 120 (Fig. 5) is to maintain the connection between shaft 47 and crank 55' only at the required moment, and also to prevent the stresses to which may eventually be subjected the oscillating disc 32, from being transmitted to shaft 47, which stresses may be due to outside causes, for example the wind.

On the other hand, the disc 32, when the coupling 120 is disconnected, has a tendency to maintain its arm 56' in the vertical position, due to

its own weight and to the distribution of the masses which contribute to its alternative movement, and is maintained in the said position, also against the action of eventual outside forces, for example the wind, by a stop 121 (Fig. 4) which acts on the return lever 56 and is carried by a pivoted lever 122, by an intermediate connecting rod 123, and by the three arms of lever 44' controlled by the weight 3 as aforesaid.

The coupling 120 (Fig. 5) consists of a female 10 piece 124 connected to the crank 55, and of a male piece 125 carried by a sleeve 126, which has a polygonal bore, and can slide on the shaft 47, the sliding portion of which has a corresponding cross-section. The sleeve 126 is constantly pressed by a spring 127 against piece 124, the movement of said sleeve being limited by the position which it may take up under the action of a fork 128 integral with one of the arms of a lever 129, the other arm of which, being provided with a hole through which the rod 43 passes, impinges against a stop 130 (Fig. 5) carried by the said rod.

The position of the stop 130 is adjusted in such a way that when the weight 3 reaches its lowermost position, the connection is automatically established in a similar manner, leaving the disc free to oscillate, the descent of weight 3 causing the stop 121 to become disengaged from the return lever 56. (Fig. 5).

From the above description it will be apparent that when the weight 37 has reached the limit of its lowest position, it is no longer able to cause the rotation of the toothed wheel 45, and consequently to actuate the signalling devices aforesaid. It becomes necessary therefore to return the weight to its former elevated position, and for this purpose is provided the mechanism C.

This mechanism (Fig. 8) is, substantially a recharging mechanism, because it reintegrates 40 the potential energy of the signalling apparatus so as to enable it to work for a given time, and also because it enables the signal to operate a second time, and it consists of a bell-crank lever 68', 68'' the fulcrum of which can revolve about 45 a collar 69 fastened to the lower part of a small iron lever 70, the ends of which are secured on two sleepers of the track, selected in a position near to the signalling apparatus B. The said sleepers may be adjoining to one another or they 50 may also include between them one or more intermediate sleepers according to the amount of pressure that it is desired to utilize.

The above said lever, which oscillates in a vertical plane in correspondence to the middle section of the small lever 70, contacts with the bottom side of the foot of rail 71, via the end of its arm 68', while its other arm 68'' is pivoted to a rod 72, which by means of an angle lever 73 (Fig. 4) actuates a secondary rod 74 pivoted on 60 the disc 15 supporting the pawls 40 above mentioned. Said disc 15 can rotate about the axis of the ratchet wheel 39, the pawls being continuously pushed against the ratchet wheel as aforesaid, by the action of spring 151.

The disc 75 is also pivotally connected through an arm 76 fixed to it to another connecting rod 77 which is pivotally connected to a revolving arm 78 (Fig. 4) the end 79 of which causes the lifting of the weight 3 by means of the tail 80 integral with it (Fig. 5). In order to maintain the lever arm 68' (Fig. 8) in constant contact with the rail, a tension spring 81 is provided (Fig. 4) which produces the desired effect by acting on the arm 76.

From the above description, which includes the case so far considered of a double line track, the working of the apparatus will be clearly understood.

- 5 When the train passes over the contact apparatus (Figs. 1, 2 and 3), both in the case of excitation due to magnets as shown in Fig. 2, and in the case of excitation due to electric cells, as shown in Fig. 3, the first axle of the locomotive 10 acting on the apparatus, produces the fall of the weight 3, which by revolving about the axis 4, produces the outward movement of the spring 62 from ratchet wheel 61 (Fig. 5) thus leaving this latter free to rotate. Simultaneously the said 15 fall causes the rod 43 to be pulled upwards, which produces the rotation of the cam 42 and causes the outward movement of the pawls 40 from the periphery of the ratchet wheel 39. In these 20 conditions, the cable may cause the free rotation of the drum 35 in the direction of the unwinding of the cable by means of the descending weight 37, which produces the rotation of the shafts 41, 48 and 49 which respectively control the armature 25 of the dynamo or alternator 50, the oscillation of the bell hammer 31 and the oscillations of the disc 32.

In order to regulate the angular speed of the said shafts, a centrifugal brake 83 is applied on the shaft 49.

- 30 In case it is desired that the lamp 35 shall flash light intermittently, it will be sufficient to insert in its circuit a suitable rotary switch, which may be actuated by the same mechanisms which actuate the dynamo or alternator 50.

- 35 In the example shown the light interruption is obtained by a rotating switch keyed to the shaft 48 and operating together with the contact springs 84 and 85.

- 40 In order to utilize to the utmost the space available in the upper part of the column 30 in correspondence with the stroke of the weight 37, this latter has a cylindrical shape having the section indicated in Fig. 9. Two grooves 87 are provided in order to allow the various parts 45 of the signal to pass through them, and the grooves 88 are guide grooves corresponding to the guide ribs provided in the column. Moreover, the suspension of the weight 37 to the cable 36 can be made elastic by means of a spring. The production of the various signals (acoustic, luminous and optical) will continue until the weight 3 is reinstated to its original position, and this occurs as soon as the first axle of the locomotive acts on the recharge mechanism C by 50 passing in front of the signalling apparatus B. When the first axle of the locomotive passes over and in correspondence to the arm 68' of the lever carried by the small lever 70, it produces, through the flexion of the rail, the lowering of said arm 60 and consequently, through the gearings above described, a pulling action on the rod 74. The movement produces on the one side, through the parts 77-78 and 79 above described, the re-lifting of weight 3 which remains again hooked thus maintaining the spring 62 in contact with the ratchet wheel 61 which stops the movement of all signalling mechanisms, and on the other hand, the shifting of the plate 75 carrying the pawls 40 with the effect of producing the effective movement of the ratchet wheel 39.

- 70 The lifting of the weight 3, produces also by means of the rod 44'', the lever 44' and the rod 43, the restoration of the cam 42 with the effect of bringing the pawls 40 into contact with the 75 teeth of wheel 38. After the rail has been lowered,

it again rises, so that the rod 74 is returned upwards through the action of the spring 79; this return movement has no influence on the weight 3 nor does it actuate the ratchet wheel 39. The successive oscillations produced on the rod 74 by the passage of the successive wheels of the locomotive and following carriages, have no effect on the position of the weight 3, but they produce the rotation of the ratchet wheel 39 and consequently of the drum 35 integral therewith, 10 in the direction of winding the cable 36 and lifting the weight 37. The connection between the drum 36 and the toothed wheel 45 being, as previously stated, loose in the movement of the drum in that direction, there is no tendency to produce 15 the rotation of the toothed wheel, and therefore the signalling mechanisms which are dependent on it remain inoperative. The apparatus is thus recharged in the manner above described, and is 20 ready to give further signals by means of the energy stored during the passage of a train over the recharge mechanism provided near the level crossing.

As the charging weight 37 has evidently an upper limit of rise, the recharge will have to be 25 stopped at that point, and to this end is provided an arrangement consisting in a lever 131, which has an arm with a hole at its end, through which passes the rod 43, and there is also provided a stop nut on said rod so that it may be lifted, 30 thereby causing the rotation of the cam 42, so that the pawls 40 become detached from the ratchet wheel 39. The other arm of lever 131 (Fig. 10) is actuated by a stop 133 carried by a wheel 134 which is fitted with a number of 35 notches 136 into which engages a tooth 137 integral with shaft 138 which carries the drum 35. The whole device is designed in such a way that when the drum 35 has completed, from the position corresponding to the maximum unwinding 40 of the cable, a given number of turns corresponding to the upper limit position of the charging weight 41, the stop 133 impinges against the corresponding arm of the lever 131, thus causing the interruption of the recharging operation as 45 hereinbefore described. In order to be able to accomplish the lifting movement of the rod 43 without meeting the resistance of the lever 44', which is kept fast by the weight 3 linked at its highest position, the rod is provided in correspondence to the pivot of its joint 158 (Fig. 5) 50 with two longitudinal grooves not shown in the drawings.

The effective stroke of the charging weight 37 and the sizes of the various parts of the apparatus will naturally be determined in such a manner that the signal may work without interruptions and during a sufficiently long time for ensuring to a greater extent the reliable working of the apparatus, as every passing train 60 discharges and recharges the apparatus to the full extent.

In the event, which likely will rarely occur, that the apparatus has not been sufficiently recharged and the weight 37 has consequently descended to the lowest limit of its stroke, the weight itself, previous to coming to a stop, will actuate a device denoting that the signal is of out of order.

This signal consists (Fig. 7) in an arm, or the like, 139 which carries a word indicating that the 70 apparatus is damaged (for example "not working") which arm is normally disposed perpendicularly along the axis of column 30, so as not to be visible, when it is not required. The said arm 139 carries at one end a pivot 140 (Fig. 6). 75

The arm 139 (Fig. 7) which is fitted with a counterweight 139' for balancing it, tends to move to the horizontal position, and is kept normally in the perpendicular position, by the action 5 of a tension wire 141 which acts on it through the lever 142, the end of which engages with an arm 143 carried by the signal itself. The tension wire 141 is secured in its lower end to a rocker 144 (Fig. 4) carried by the column, and 10 passes through a hole made through a small block 145.

The end of the lower arm 147' of a bent lever (Fig. 4) the other arm of which 147'' is placed in the path of the charging weight 37, presses 15 constantly by the action of a spring 148 on said tension wire 141 so as to prevent it from sliding inside block 145 and consequently to move. When the weight 37 reaches its lowermost position it impinges against arm 147'' overcoming 20 the action of the spring 148, (Fig. 4) the arm 147' frees the wire 141, and the signal arm 139 drops to the horizontal position thus showing the lettering marked on it. The signal may afterward 25 be return to its normal position by hand. For the purpose of preventing, in case of prolonged damage, the recharge mechanism continuing to work when the trains are passing, the mechanisms of power supply, and also for preventing 30 a useless wear of the said parts, there may be provided a mechanical connection between the lever 147'-147'' and the rod 43, so that when the cable 141 is lifted, it also lifts simultaneously 35 said rod so as to disconnect the pawls 40 from the wheel 39 and to keep them detached during the time while the signal "not working" is in sight. This latter device is not shown in the drawings.

In the case in which the current is supplied by 40 electric cells, shown schematically in Fig. 3, it may happen, due to some other cause, apart from the passage of a train at A, that the current may fail in the circuit of electromagnet 1. In case this failure is due either to exhaustion 45 of the cells 8', or to the breakage of the wires 17 and 20, and the signalling apparatus B will start its signals in the same manner as if an interruption had occurred between 7 and 9, (Fig. 1) and unless it is recharged by the passage of a train in C, its charging weight will fall down 50 (Fig. 4) until it presses on the arm 147'' which renders visible the signal "not working" as heretofore described.

From the above description it is apparent that 55 the safety is absolutely insured, as in case of damage, the apparatus indicates in a visible manner that it is out of order, or during a short time, corresponding to the time required for lifting weight 37, to descend to its lowermost 60 position, the signal will indicate danger in the same way as if a train was approaching.

The manner of working described so far has 65 reference to the case of a double track railway line, that is to say, to the case in which the trains on each track run always in the same direction, so that each track is provided with only one contact apparatus applied at a point preceding the level crossing in the direction of the trains.

In case of a single track there must be 70 provided two contact apparatus on either side of the level crossing, so as to signal the arrival of the trains that may approach from either directions, and in this case it is necessary to add an auxiliary appliance in order to prevent the train, after having stopped the signalling device and

recharged the apparatus by passing over the level crossing, starting the said devices when passing over the other contact apparatus.

This device is shown schematically in Fig. 11, 5 for use in connection with excitation current supplied by electro-magnets, and comprises an electromagnet 91, a heavy sphere 92 and a contact rod 93 which cooperate with the electro- 10 magnet 1 and with the weight 3 of the apparatus described above. The weight 3 is connected 15 with the weight 92 by means of a rod 94 pivotally connected at one side with an arm 95 integral with the weight 3, and at the other side the rod 94 is engaged in a hole provided on the arm 96 of a lever turning round a pivot 98, 15 the other arm 99 of which actuates by means of a connecting rod 100, the contact lever 93 rotatable about 101. Suspended from an arm 97 forming part of the lever 96-99 is the weight 20 92 which is also rotatable round the pivot 98, so that the movement of the weight 3 produces the movements of the sphere 92 and of the contact rod 93. The coupling between the rod 94 and the arm 96 consists in a tooth which 25 impinges against the arm 96 in the required direction for producing the lifting of the weight 92, leaving loose the coupling during the reverse movements of the rod, thus allowing the movements to take place as hereinafter described.

The electromagnet 91 attracts, in a similar manner as the electromagnet 1, a small armature 103 which is provided to keep raised, at the right moment, the weight 92. The contact lever 93 has for its object, when rotated, to establish the 30 contacts so as to direct the current to one or the other of the magnet-generators 1 and 91, closing in the first case the circuit: earth-magnet-generator-17-104-105-106-1-earth, and in the second case the circuit: earth-magnet-generator-17'-17-104-108-91-earth. 35 It is to be noted in this case that the conductor 17 is formed by the rail, suitably insulated from the ground and by portions of the same rail in which the signalling section is included.

The apparatus operates in the following way: 45

When the signalling apparatus is in the position of rest, the weight 3 is in its highest position, the weight 92 is lowered and the contact lever is in the position shown in the figure, in which the current passes to the electromagnet 50 1. When the first axle of the train passes A, and causes a current impulse to flow in the circuit from the electromagnet 8', this current circulating through the coil of the electromagnet 1 will produce the fall of the weight 3 and 55 simultaneously also the lifting of the weight 92 which will thus be held by the armature.

It will be understood that at the same moment the signals will start to operate, as nothing is changed in the apparatus that has reference 60 to it. The movement of the weight 92 has caused the contact rod to close the circuit of the electromagnet 91, simultaneously breaking the circuit of the electromagnet 1. When the train passes over the level crossing the emission 65 of the signals ceases owing to the lifting of the weight 3 produced by the recharge device, and when the train leaves the signalling zone, the current that is sent out from the signalling apparatus does not produce the lowering of the 70 weight 3, because the circuit of electromagnet 1 is interrupted; however the train itself causes with its last axle the fall of the weight 92. With this last mentioned movement the apparatus returns to its primitive position and is ready for 75

giving a new signal. The last axle of the train only produces the fall of the weight 92, because so long as there is an axle over the portion corresponding to the rail section at A, this axle short circuits the armature 14 of the magneto-electric machine 8' through the other rail which is connected electrically with it, and the current no longer reaches the signalling apparatus.

In all the above description it has been assumed that there is one signal, applied for example to a level crossing, to be used for signalling trains which run only in one direction. When considering however the general practical case in which the level crossing is to be provided with two signals, one at each side of the railway line, each of which is to be capable of signalling the approach of trains running in either directions, the apparatus suitable for this purpose is not substantially different than the one previously described.

I claim:

1. In an automatic signalling device for railway crossings of the type comprising a first and a second conveniently spaced separate section of trackway, the combination with a rotatable drum and a weight suspended from a cable wound on said drum and adapted to be lowered and moved to a raised position, of a pedal provided in the first track section, an electromagnet having an armature for normally holding said weight in its raised position, said electromagnet receiving current impulses only when the wheels of the train pass over said pedal, an electro-magnetic device, such as a magneto used for internal combustion engines for generating the electric current, said impulses being produced by the flexion of the

rail, and a suitable transmission for transmitting said current impulses to the solenoid of said electro-magnetic device, the said current impulses producing the release of the armature normally holding said weight in its raised position, thus permitting the lowering of said weight. 5

2. The combination as specified in claim 1, in which the signal indicating the approach of a train comprises an optical signal composed of an arm and an oscillating disc held thereby, a 10 light signal consisting of a lamp carried by said disc and so disposed as to deliver a continuous or intermittent light, and an acoustic signal consisting in the ringing of a bell or the like.

3. The combination as specified in claim 1, in 15 which to prevent said weight, raised by the alternative flexions of the rail produced by the passage of the train wheels thereover, from rising above its topmost position there is provided a means for disconnecting the transmission of the 20 movement to said drum as said weight is about to reach its topmost position, and in case the lowermost position of said weight is exceeded preventing its being re-lifted by the passage of another train, the descending weight, before coming to a stop, actuates an "out of order" signal. 25

4. A plurality of signalling devices as specified in claim 1, applied to a level crossing in which the electromagnets of each signalling device are connected in series in a single circuit, said circuit 30 being closed as a train approaching from either direction of the level crossing on a double track railroad, passes over the first rail section and being opened when the train has passed over the second rail section. 35

ARISTIDE RICCARDI.
